UNITED STATES PATENT OFFICE.

CHARLES L. LOVERCHECK, OF INDIANAPOLIS, INDIANA.

ENVELOP-FILLING MACHINE.

1,122,519.

Specification of Letters Patent. Patented Dec. 29, 1914.

Application filed December 22, 1913. Serial No. 808,217.

To all whom it may concern:

Be it known that I, CHARLES L. LOVERCHECK, a citizen of the United States, and a resident of Indianapolis, county of Marion, 5 and State of Indiana, have invented a certain new and useful Envelop-Filling Machine; and I do hereby declare that the following is a full, clear, and exact description thereof, reference being had to the accompanying drawings, in which like letters refer to like parts.

The object of this invention is to fill envelopes and the like with circulars or letters and seal the envelopes mechanically, rapidly 15 and, therefore, economically. It is adapted for use by those who mail circulars or letters in large numbers. Also this invention contemplates filling the same envelopes with a plurality of different kinds of circulars or 20 letters in the same operation of the machine.

A feature of the invention consists in providing means for feeding envelopes successively through the machine, opening the flap of each envelop at the beginning of the 25 operation and temporarily stopping the envelop during its progress through the machine in position or positions to receive the circulars or letters. Beside the path of the envelopes through the machine, one or more 30 circular or letter holders are located from which the machine feeds them in succession to and into the envelopes during their temporary stoppage in transit through the machine. One of these circular or letter holders 35 may be employed or in greater numbers and if more than one circular or letter holder is employed, the machine enables one to fill their envelopes with letters or circulars of different character, each holder having a different kind of circular or letter. Means are provided for feeding a single circular or letter at a time transversely of the 40 machine toward and into the envelopes. Envelops issue from the machine filled, but with the flaps open and the same are sealed, or tucked in, if not intended to be sealed, by hand or otherwise.

The foregoing features of the invention enable the machine to fill envelopes very rapidly, a great many per minute.

The full nature of the invention will be understood from the accompanying drawings and the following description and claims.

55 In the drawings, Figure 1 is a plan view of the machine with the motor omitted. Fig.

2 is a side elevation thereof with the motor in place. Fig. 3 is a vertical longitudinal section on the line 3—3 of Fig. 1. Fig. 4 is a horizontal transverse section on the line 4—4 of Fig. 2. Fig. 5 is a section on the line 5—5 of Fig. 4, with parts broken away. Fig. 6 is a side elevation of part of the machine from line 6—6 of Fig. 4. Fig. 7 is a vertical transverse section on the line 7—7 of Fig. 1. Fig. 8 is a vertical transverse section on the line 8—8 of Fig. 1. Fig. 9 is a vertical longitudinal section on the line 9—9 of Fig. 8. Fig. 10 is a section on the line 10—10 of Fig. 1.

The machine includes suitable end supports 10 and 11 and a lower platform 12 which carries an electric motor 13 from which power is transmitted by a belt 14 to a sheave wheel or pulley 15 which may be called the drive wheel of the machine. Upon said supporting means the machine frame proper rests and is secured consisting of side plates 16 and 17, see Fig. 8, which extends longitudinally of the machine for the entire length thereof, as seen in Figs. 1 and 2, and cross frames 18, 19 and 20 are secured between and to said side frames to make a rigid frame. The cross frame 20 is at the discharge end of the machine and has an opening 21 through which the envelopes discharge, see Fig. 4. At the extreme right-hand end of the machine, as shown in Figs. 1 and 3, the cross plate 18 is located extending only for a portion of the height of the total frame. The side plates 16 and 17 are cut away at their upper right-hand corners, as shown in Fig. 2, so that there is a lower extension, as seen in Figs. 2 and 3, and the cross plate 19 extends from the top of the side plate 16 down to a level with said lower extension, as seen in Fig. 3, and has a slot 22 in the lower portion thereof through which the envelopes enter the machine. There are two intermediate plates 23 and 24 in said frame which extend longitudinally and horizontally thereof, as shown in Figs. 1, 3, 7, 8 and 9, to form a guideway for the envelopes to pass entirely through the machine from the right-hand end of Fig. 1 to the left-hand end thereof. To that end said upper plate 24 is spaced from the lower plate 23, as seen in Fig. 3. These plates are parallel with each other and the lower plate is in alinement with the upper part of the lower extension of the frame shown in Figs. 2 and 3, and the feeding rolls

are located above and below said guide plates 23 and 24, as will hereafter be explained.

At the right-hand end of the machine an envelop holder is mounted, consisting of a pair of transverse bars 25, see Fig. 3, which are secured to the underside of the inwardly turned flanges of the side walls 16 and 17 of the machine frame, and longitudinal bars 27, three being shown in Fig. 1, are secured 10 on said cross bars 25, as shown in Fig. 3, and on each side of the cross bar 25 said bars 27 are bowed upward, as shown in Fig. 3, and have free projecting ends, although said bars 27 are stiff. There is a pair of vertical rods 28 secured rigidly to arms 29 which are secured to the top of the side frame 16, as shown in Fig. 1, and a pair of vertical rods 30 is secured to arms 31 adjustably mounted on a short plate 32 which 15 is secured upon the cross bars 25 near one side of the machine, as appears in Fig. 1. The arms 29 and 31 are arranged so that they can be adjusted and, therefore, the position of the rods 28 and 30 can be adjusted 20 to suit envelops of different sizes, for the envelops 33, indicated by dotted lines in Fig. 3, are placed between said two pairs of rods and longitudinally of the machine with the flaps located on the side next to the rods 30, or rear side of the machine, as viewed in Fig. 1. One envelop is shown by dotted lines in Fig. 1, after it has been started into the machine and that illustrates where the flap is located. The arrangement is such, 25 as appears in Fig. 3, that the lower envelop of the pack will be fed to the left into the guideway of the machine.

The means for feeding the lower envelop from the pack into the machine is shown in Fig. 3, and consists of a wood roller 35 secured on a shaft 36 and a rubber covering 37 on said roller with a pair of radial segmental projections 38 thereon. These segmental projections when revolved project 40 up between the longitudinal bars 27 and into engagement with the lower envelop so as to feed it from under the group of envelops into the guideway.

The upper envelops are prevented from being fed by a fixed bar 40 which is secured to the end plate 19 and in connection with said fixed bar there is a vertical tube 41 which is square in cross section so that a rubber piece 42 can be inserted and held therein and extend down to the guideway below to prevent any but the lowest envelop from being pressed. The lower end of the rubber piece 42 is beveled so as to make it sensitive to the action of the envelops.

Soon after the envelop enters the guideway through the machine it passes between the pair of feed rolls, which grip it and feed it on through the guideway. There are two series of these feed rolls, one series 44 above and one series 45 below the guideway. All

of these feed rolls may be made alike, consisting of an inner cylinder of wood 46 secured on shafts 47 and 48, respectively, and having an outer sleeve or layer of rubber 49 secured thereon. The upper rolls project through a slot 50 in the upper plate 24 of the guideway, and the lower rolls project through a slot 51 in the lower plate 23 of the guideway. The shafts 48 below the guideway are mounted at one end in the side wall 16 of the frame and carry on said ends pinions 52. The other ends of said shafts 48 are mounted in arms 53 which extend inward from the inner surface of the side plate 17 of the main frame as shown in Fig. 7. Therefore, the lower series of feed rolls 45 are not vertically adjustable. The upper shafts 47 for the upper rollers 44 are mounted so as to be vertically adjustable, as shown in Fig. 7, that is, they are mounted at one end in a bearing 55 vertically slidable between guides 60 and pressed downward by a spring 57 adjustably mounted in a lug 58 extending from the inner surface of the frame plate 17. At the other end said shafts 47 are mounted in a similar bearing 55 vertically slidable between guides 60 on the plate 17 and similarly spring controlled. Hence, the upper rolls 44 are spring pressed downward on the lower rolls for feeding purposes.

In the driving mechanism, see Fig. 2, the driving wheel 15 is mounted on one of the shafts 48 and power is transmitted from the pinion 52 on the driving one of the shafts 48 to the pinions 57 on the other shafts 48 by a series of three intermediate gears 61, 62 and 63. In all of the groups of said wheels 61, 62 and 63 they are arranged in a straight transverse line excepting at the right-hand end where the wheel 62 is above in order to bring the two right-hand shafts 48 closer together than any other pair of shafts 48. These gears 61, 62 and 63 are mounted in the frame plate 16. There is also a gear 64 mounted in said plate near the right-hand end and driven by the pinion 52 on the right-hand shaft 48 and it transmits power to a pinion 65 on the shaft 36 which feeds the envelops in the machine.

The means for feeding the circulars or letters in the machine and into the envelops is as follows: There is a horizontal side frame secured to the outer side of the frame plate 17, as shown in Fig. 7, and extending for a portion of the length of the machine, as shown in Fig. 1, and this side frame consists of a series of brackets or plates 67 extending transversely away from the plate 17 and having a longitudinal bar 68 secured to the outer ends thereof. There is one bracket or plate 67 opposite each set of feed rolls, see Fig. 1, and between each pair of brackets 67 there is a circular or letter holding frame 70 secured by screws 71 upon the bar 130

68. Each holder 70 has three inwardly extending arms 170, the inner ends of which project through a slot 72 which extends for almost the entire length of the side plate 17, and the inner ends of the arms 170 are turned downward, as shown in Fig. 7. To hold the circulars 73, shown by dotted lines in Fig. 7, in place on said frame 70, there is on the outer side a pair of vertical arms 74 with the lower ends turned inward and longitudinally and provided with longitudinal slots 75, see Fig. 7, to which the screws 71 extend so that the posts 74 can be adjusted and clamped in position. At the end of each frame 70 there is a U-shaped frame consisting of a lug 76 secured by a screw 77 on the bracket 67 and having a horizontal portion 78 and two posts or fingers 79 which extend upward therefrom, see Figs. 1 and 7. The lug 76 is slotted so that the posts 79 may be adjusted to suit the length of the circulars or letters.

The circulars or letters are fed transversely of the machine into the machine and envelops by the feeding segments 80 on a rubber sleeve 81 surrounding and secured to wooden rolls 82 which are secured to a shaft 83, as shown in Fig. 7, and which is mounted in bearings, not shown, secured to the underside of the brackets 67, see Fig. 1, and also in the arms 84 extending from the plate 17. Said shaft 83 is driven by a beveled gear 85 on the shaft 36 and gear 86 on the shaft 83. The reason for the segmental arrangement of the envelop feeding means 88 and the circular feeding means 80 is to cause them to feed intermittently and at the right time. The envelops do not enter in close succession, nor do the circulars as they are fed one at a time only when an envelop is in place to receive the circular. Therefore, one envelop and one circular is fed during each revolution of the shaft 36 or 83 and these shafts are geared to the same speed. More than one letter or circular is prevented from being fed into the machine at a time by rubber fingers or pieces 140, see Fig. 7, which are held in guides or holders 141 secured to the outer surface of the frame plate 17 and having a post 142 projecting upward therefrom. There are two of these pieces of rubber and two of said posts for each holder and said posts coöperate with the other posts 74 and 79 in holding the circulars or letters. The posts 142 are not essential, but flexible means like the rubber finger 140 are essential for the purposes stated.

When a circular or letter is fed in through the slot 72, see Fig. 7, its advancing edge passes between lower rubber feed rolls 90 and 91, see Fig. 8, which extend longitudinally of the machine and their meeting edges lie at the left about one-sixteenth of an inch lower than the upper surface of the lower

guide plate 23, see Fig. 8. Said guide plate 23 has its right-hand edge, as shown in Fig. 8, turned down to form a lip 92 for the entire length of the machine, as shown in Figs. 1 and 8. The purpose of this will be 70 explained later. The feed rolls 90 and 91 are mounted on a pair of parallel shafts 94 and 95 which extend almost through the machine. The lower shaft 95 is mounted in arms 96 extending inward from the plate 75

17. The upper shaft 94 is mounted in bearings 97 which are vertically slidable in the lower arm of the bracket 56 and which are pressed downward by springs 98 which are adjustably mounted at their upper ends in 80 the arm in said bracket 56, see Fig. 7. There is any desired number of the rolls 90 and 91, there being a pair on each shaft 94 and 95 opposite each circular or letter holder, see Fig. 1. The lower shaft 95 is driven by a 85

beveled gear 99, see the left-hand end of Fig. 1, which meshes with a beveled gear 100 on a stub shaft 101 mounted in the plate 17 and carrying a pinion 102 on its outer end which meshes with a pinion 103 on a shaft 90 104 extending through the machine, see Figs. 4 and 6, and carrying on its other end a pinion 105 which engages a gear 106 on the left-hand shaft 48. The stub axle 101, see Fig. 4, is held in place by an arm 108 95 secured to the plate 17. As the envelop enters the guideway through the machine and moves to the dotted line position shown in Fig. 1, the flap of the envelop is opened by a plate 110 which is seen in Fig. 1. The plate 110 is integral with or secured to the top guide plate 24 and it is spirally disposed or in the form of a plow share or flange of an auger, turning from a horizontal position almost 180°, which gradually forces the 1 flap of the envelop open and turns it back beyond a horizontal position and down. The rear bar 27, seen at the upper right-hand corner of Fig. 1, is made of spring metal and projects to the right-hand end of the plate 110 and is at that point sprung up somewhat higher than said end of plate 110 so as to be sure to hold the flap of the envelop high enough to insure it passing above the left-hand end of plate 110 instead of below it. As the envelop goes through the machine, the flap is held down in its open position by a bar 111 which extends longitudinally of the machine just below the inner edges of the lower series of feed rolls 91 and is held in place by arms 112 secured to the inner surface of said frame plate 17, as shown in Figs. 7 and 8. This leaves the mouth of the envelop open to receive a circular or letter. As the envelop is fed on 120

through the machine after the flap has been opened by the cam plate 110, it is stopped temporarily in front of the first circular or letter holder. The means for stopping the envelop in such position so as to receive a 130

circular or letter consists of two stops 115 projecting downward through openings 116 in the top guide plate 24, see Fig. 1. These stops project through the guideway in the path of the envelop and they are divergent arms of a lever formed of a slotted hollow portion 117 and another portion 118 projecting into the hollow portion and held in adjusted position by a set screw 119, whereby the length of the lever and the position of the stops can be predetermined. The lever is rigidly secured on a shaft 120 mounted in bearings 121 extending up from the guide plate 24 and on said shaft 120 there is an arm 122 rigidly secured, the free end of which rides upon a cam 123 mounted on a shaft 124 which extends transversely through the machine and has bearings in the side frame plates 16 and 17 and is driven from the gearing heretofore described and shown in Fig. 2, through wheels 125. There is one of these shafts 124 opposite the middle portion of each holder for circulars and envelopes. The cam 123 is illustrated by dotted lines in Fig. 9, and it is formed with one cam projection adapted by acting on the arm 122 to raise the stops 115 and permit the envelop to be moved on its way, but during nearly the whole rotation of the shaft 124 the stops 115 are down in position to stop an envelop, as shown in Fig. 9. The envelop is stopped between pairs of feed rolls 44 and 45 and out of engagement with them. While the envelop is held for its period of time, a circular or letter is fed laterally by the means heretofore described and shoved into the envelop. At that time there is nothing pressing down on the envelop and the flap is held turned downward as heretofore explained, so that the mouth of the envelop gaps and permits a circular or letter to enter the envelop. Of course, for rapid operation the letter or circular should be small enough to readily enter the envelop without catching on the ends thereof. After the circular or letter has entered the envelop it is necessary that the envelop be fed to the next set of feed rolls 44 and 45. This is done by a rubber cam-like projection 130 on the feed rolls 131 secured on the shafts 124 and 132. The latter shafts 132 are located below the guideway and mounted transversely of the machine in the side frame plates 16 and 17 and are driven by all of the gears 62 heretofore described excepting the one near the right-hand end of the machine, see Figs. 1 and 2. These projections 130 from the feeding rolls 131 operate through openings 134 in the guideway plates 23 and 24, see Fig. 9, and thus come in frictional engagement with the envelop and feed it to the next feed rolls 44 and 45 which feed the envelop until again stopped opposite the next holder for circulars and letters, if there be more than one such holder.

This operation can be repeated for any desired number of holders, from one up. As here shown only two such holders appear, but in the machine heretofore built by me there are four such holders for circulars and letters so that with such machine, four different kinds of circulars or letters can be inserted in the same envelop and cards can be inserted in the envelopes as well as flexible circulars and letters. Of course, when circulars and letters are to be inserted in envelopes, they must be folded before they are put in the holders and preferably folded so that each one will be as compact as possible so as to be stiff enough to feed straight into the envelop. The projection on the cam 123 extends in a direction opposite to the projection 130 on the feed rolls 131, as shown in Fig. 9, and they are so arranged that the cam 123 will lift the stops 115 just before the projection 130 comes into feeding engagement with the envelop and, as is obvious from the drawing, the cam 123 permits the stop soon, however, to drop, but it merely rides on the envelop without interfering with its feeding movement. The machine operates at rather considerable speed so that the envelop is fed rather rapidly and as it leaves one pair of rolls 44 and 45, they in effect pitch it on end-wise against the stops 115. Therefore, the machine will feed envelopes of somewhat varying lengths very satisfactorily.

The feeding projection on the rolls for feeding the circulars or letters and on the rolls for starting the envelopes after the circulars or letters have been introduced in them are so arranged as to work in harmony, that is, they project upward at the same time and that causes the two projections on the rolls for the circulars to accomplish their feeding in advance of the projections on the other rolls referred to and after the feeding projections for the circulars have done their work, then the feeding projections on the other rolls engage the envelopes and start them through the regular feeding rolls 44 and 45. The means for feeding the envelopes from the envelop holder, the means for feeding the circulars and letters from the circular holder, and the means for starting the envelopes after the circulars have been put in them, all are geared to operate at the same speed, and their rotation is coterminous. The feed rolls 44 and 45 and also the little feed rolls 90 and 91 operate continuously and in fact all of the feed rolls operate continuously, but those for feeding the envelopes and circulars from their holders and for starting the envelopes after the circulars are in them, have projections which meet only for a short portion of the revolution of the feed rolls on which they are located, and, therefore, these feed rolls act intermittently while the feed 130

rolls 44 and 45, and 90 and 91 operate so as to act at any time if there is an envelop or circular in position to be acted upon by them.

6. To enable the machine to operate satisfactorily on envelops of varying widths, the posts 28, see the right-hand end of Fig. 1, can be adjusted toward or away from the other posts 30 by altering the position of the arms 29. There is also a guide 150 secured on the inside of the frame plate 16 for guiding the edges of the envelops after they have left the posts 28 and until they get into the guideway of the machine, and this plate 150 is adjusted by set screws 151. For varying lengths of envelops the only adjustment required is that of the lever elements 117 and 118 so as to change the position of the stops 115 and enable them to stop the envelops 20 at the right positions beside the circular holders.

The invention is:

1. An envelop filling machine including means for holding a number of envelops, 25 intermittently operating means for separating one envelop at a time from said number of envelops and feeding such separated envelop through the machine, means for holding the flaps of each envelop open after it has been separated from the other envelops and as it moves through the machine, and means for moving circulars and the like into such separate envelop while it is temporarily stopped during its progress through the 35 machine.

2. An envelop filling machine including means for holding a number of envelops, intermittently operating means for separating one envelop at a time from said number of envelops and feeding such separated envelop through the machine, means for holding the flaps of each envelop open after it has been separated from the other envelops and as it moves through the machine, means 45 for temporarily stopping the movement of such envelop after it has been separated and the flap has been opened, and means for feeding circulars and the like into the envelop while it is stopped.

50 3. An envelop filling machine including a series of means for feeding the envelops through the machine, means for holding the flaps of the envelops open, means for stopping the envelops intermittently between the feeding means, means for feeding circulars or the like into the envelops while stopped, and means for starting each envelop after it is stopped and move it to the next feeding means.

55 4. An envelop filling machine including means for holding a number of envelops, intermittently operating means for separating one envelop at a time from said number of envelops and feeding such separated envelop through the machine, a holder for cir-

culars and the like located at the side of the machine, means for holding the flap of said envelop open after it has been separated from the other envelops, means for stopping said envelop after its flap has been 70 opened and opposite said circular holder and means for feeding a circular or the like from said holder into such envelop while it is stopped.

5. An envelop filling machine including 75 means for feeding separate envelops successively through the machine, a plurality of holders for circulars or the like on the side of the machine, means for holding the flaps of the separate envelops open, means 80 for stopping each envelop opposite each circular holder, and means for feeding circulars or the like from all of said circular holders simultaneously into the separate envelops opposite said circular holders. 85

6. An envelop filling machine including means for feeding envelops through the machine successively, a spirally disposed plate for opening and turning the flaps of the envelops more than ninety degrees so 90 that the mouths of the envelops will be open, and means for thereafter holding the flaps of the envelops open.

7. An envelop filling machine including a pair of guide plates for forming a guideway through the machine for the envelops, means for feeding the envelops successively through said guideway, and a spirally disposed plate secured to one of the guide plates at the entrance of the guideway in position so that the flaps of the envelops will pass above the forward end of said spiral plate and be thereby opened and turned back more than ninety degrees. 95

8. An envelop filling machine including 100 a pair of guide plates for forming a guideway through the machine for the envelops, means for feeding the envelops successively through said guideway, a spirally disposed plate secured to one of the guide plates at the entrance of the guideway in position so that the flaps of the envelops will pass above the forward end of said spiral plate and be thereby opened and turned back more than ninety degrees, and a spring bar 105 near the front end of said spiral plate and over which the envelop passes for holding the flap edge of the envelop so that the flap cannot pass into said guideway but must pass over said spiral plate. 110

9. An envelop filling machine including 115 a pair of guide plates for forming a guideway through the machine for the envelops, means for feeding the envelops successively through said guideway, a spirally disposed plate secured to one of the guide plates at the entrance of the guideway in position so that the flaps of the envelops will pass above the forward end of said spiral plate and be thereby opened and turned back more than 120 125 130

- ninety degrees, and a bar extending from the inner end of said spiral plate for the length of the machine and located so as to hold the flaps of the envelopes open while they are passing through the machine.
10. An envelop filling machine including a pair of guide plates for forming the guideway for the envelopes through the machine, one of said guide plates having a downwardly turned lip, a spirally disposed plate secured to the other guide plate in position to open the flaps of the envelopes as they enter the guideway and turn them down over the lip portion of the other guide plate, means extending from said spirally disposed plate for the length of the machine for holding said flaps turned over the lip on said guide plate, means for intermittently feeding the envelopes successively through the machine, and means for inserting circulars or the like into the envelopes as they pass through the machine.
11. An envelop filling machine including a guideway through which the envelopes may pass through the machine, an envelop holder at one end of said guideway, a circular holder located beside said guideway, means for stopping the envelop in said guideway opposite the circular holder, means for feeding the envelopes successively through the guideway, means for intermittently feeding the envelopes from the envelop holder, means for intermittently feeding the circulars from the circular holder into the envelop, and means for operating the means for feeding the envelopes and circulars from their holders at the same speed.
12. An envelop filling machine including a guideway through which the envelop may pass through the machine, an envelop holder at one end of said guideway, a circular holder located beside said guideway, means for stopping the envelop in said guideway opposite the circular holder, means for feeding the envelopes successively through the guideway, means for intermittently feeding the envelopes from the envelop holder, means for intermittently feeding the circulars from the circular holder into the envelop, means for starting the envelopes after they have been filled with the circulars or the like, and means for operating the means for feeding the envelopes and circulars from their holders and the means for starting the envelopes after being filled, at the same speed.
13. An envelop filling machine including a guideway, through which the envelopes are moved through the machine, a spiral plate at the entrance of said guideway and to one side thereof for opening the flaps of the envelopes, and an adjustable bar at the other side of the guideway and extending through the machine for adjusting the guideway to suit the size of the envelopes.
14. An envelop filling machine including a pair of plates for forming a guideway through the machine for the envelopes, said plates having openings at intervals greater than the length of an envelop, feeding rolls operating in said openings, and means for stopping the envelopes between said openings and feeding rolls.
15. An envelop filling machine including a pair of plates for forming a guideway through the machine for the envelopes, said plates having openings at intervals greater than the length of an envelop, feeding rolls operating in said openings, means for stopping the envelopes between said openings and feeding rolls, and means located beside the portion of the guideway between each pair of openings and feed rolls for feeding circulars and the like into the envelopes.
16. An envelop filling machine including a pair of plates for forming a guideway through the machine for envelopes, said plates having openings at intervals greater than the length of an envelop, feeding rolls operating in said openings, a stop adapted normally to project into said guideway for stopping the envelopes between said openings and feed rolls, means for inserting a circular or the like in said envelop while it is stopped, means for starting the envelop after the circular is in it to move it to the next feed roll, and means for removing the stop while the envelop is being started.
17. An envelop filling machine including a guideway for the envelopes through the machine, feed rolls located at intervals greater than the length of the envelop and entering said guideway for feeding the envelopes therethrough, a lever provided with stops on the end thereof and adapted normally to project through said guideway for stopping the envelopes through said feed rolls, so that their momentum will not carry them to the next feed roll, a revolving shaft mounted parallel with said guideway, means carried by said revolving shaft adapted to project into the guideway and at one point during the revolution to engage the envelop therein and start it, and a cam on said revolving shaft for operating said lever and withdrawing the stops just before said starting means begins to operate.
18. An envelop filling machine including a guideway for the envelopes through the machine, feed rolls located at intervals greater than the length of the envelop and entering said guideway for feeding the envelopes therethrough, a lever provided with stops on the end thereof and adapted normally to project through said guideway for stopping the envelopes through said feed rolls, so that their momentum will not carry them to the next feed roll, a shaft mounted parallel with said guideway, means carried by said revolving shaft adapted to pro-

ject into the guideway and at one point during the revolution to engage the envelop therein and start it, and a cam on said revolving shaft for operating said lever and withdrawing the stops just before said starting means begins to operate, said stop lever being so formed as to adjust the position of the stops for envelopes of varying lengths.

19. An envelop filling machine including a guideway formed of upper and lower plates with openings therein, feed rolls located at intervals greater than the length of the envelop and operating in said guideway for feeding the envelopes therethrough, a stop lever fulcrumed on the upper guide plate longitudinally adjustable and having turned down ends held by gravity normally in said guideway for stopping an envelop between said feed rolls and having an actuating arm, a revolving shaft mounted above said upper guide plate with means thereon adapted at one time during each revolution to engage the envelop in the guideway and start it, and a cam on said revolving shaft for engaging the actuating means of said lever and lifting the stops out of the guideway when the envelop is to be started.

20. An envelop filling machine including a guideway through which the envelop passes through the machine, means for feeding the envelopes therethrough intermittently, means for stopping the envelopes during their passage through the machine, circular holding means located beside the

guideway at the point where the envelop is stopped, a pair of feed rolls extending longitudinally of the machine and located near the side of the guideway and with their meeting edges slightly below the entrance to the guideway, and means for feeding the circulars or the like from the circular holder through said longitudinal feeding means so that they may feed a circular or the like into the envelop.

21. An envelop filling machine including a guideway through which the envelop passes through the machine, means for feeding envelopes therethrough intermittently, means for stopping the envelopes during their passage through the machine, circular holding means located beside the guideway at the point where the envelop is stopped, a pair of feed rolls extending longitudinally of the machine and located near the side of the guideway, means for continuously driving said longitudinal feed rolls, and intermittently operated means for feeding a circular or the like from a circular holder to said longitudinal feed rolls so that the latter will feed the circular or the like into the envelop while in the guideway.

In witness whereof, I have hereunto affixed my signature in the presence of the witnesses herein named.

CHARLES L. LOVERCHECK.
